WASHER PLACING MACHINE

Wilbert H. Patten, Trenton, N. J., assignor to
 Trent Machine Company, Trenton, N. J., a corporation of New Jersey

Application March 7, 1936, Serial No. 67,685

16 Claims. (Cl. 18—1)

This invention relates to an improved washer placing machine, and more particularly to a machine of this kind which is adapted for use in placing nailing washers on the pins of rubber heel producing molds.

An object of the invention is to provide an improved washer placing machine having novel washer feeding means including a main finger pivoted for lateral swinging movement and a second finger carried by the main finger and adapted for lateral swinging movement relative thereto.

Another object of the invention is to provide a washer placing machine having a novel arrangement of washer feeding fingers including a pair of fingers adapted for relative lateral swinging movement and interconnected by proportional movement mechanism.

A further object of the invention is to provide an improved washer placing machine having a frame with a member thereon movable about pivot means extending transversely to the longitudinal axis, and wherein washer feeding fingers carried by such pivoted member are adapted for relative lateral swinging movement and are interconnected by proportional movement mechanism.

Still another object of the invention is to provide an improved washer placing machine having a plane-like or foot-like frame with a novel arrangement of washer feeding fingers thereon.

Other objects and advantages of the invention will be apparent from the following description, when taken in conjunction with the accompanying sheets of drawings, wherein—

Fig. 1 is a top plan view, with portions broken away, showing a washer placing machine embodying my invention.

Fig. 2 is a longitudinal sectional view thereof taken on line 2—2 of Fig. 1.

Fig. 3 is a partial sectional view taken through the washer feeding fingers as indicated by line 3—3 of Fig. 1.

Fig. 4 is a bottom plan view of my improved washer placing machine.

Fig. 5 is a side view of one of the main washer feeding fingers looking in the direction indicated by the line 5—5 of Fig. 1, and

Fig. 6 is a sectional view taken through one of the main washer feeding fingers as indicated by line 6—6 of Fig. 1.

More detailed reference will now be made to the accompanying drawings wherein I have shown one embodiment of my improved washer placing machine. It will be understood, of course, that the machine shown in the drawings is by way of example only and that the invention may be embodied in various other machines and apparatus of this general type.

As shown in the drawings, my improved washer

placing machine may be provided with a plane-like or foot-like body 10 which forms the frame of the machine and supports a plurality of washer feeding devices or fingers 11, 12 and 13. During use of the machine the body 10 is manually, or otherwise, moved over a mold member having projecting pins, and during such movement washers are automatically placed on the pins by the fingers.

The frame 10 may be provided with a substantially flat bottom plate which, in general appearance and outline, may correspond roughly with the sole of a shoe or the bottom plate of a plane. The heel end of the frame, which is also the forward or leading end, may be constructed with a hollow part 15 which houses certain finger carrying mechanism to be described hereinafter and provides a connection for an operating handle 16. It will be understood, of course, that the bottom plate may be formed integral with the frame 10, or for convenience of manufacture, may, as shown in this instance, be formed by plate sections 17 and 18 which are connected to the bottom of the frame by screws or other suitable fastening members. The plate section 17 is preferably of a size and shape to form a cover for the bottom of the hollow frame part 15. The plate section 18 has an opening 19 therethrough in which the fingers 11 and 12 operate and an opening 20 in which the finger or device 13 operates. Frame portions 21 extend rearwardly from the hollow part 15, that is toward the toe end 21', and form an upstanding flange around the openings 19 and 20.

For operably mounting the fingers 11 and 12 I may provide a finger carrier which is in the form of a movable member 22. As shown in Figs. 1 and 2 the member 22 may be a frame-like part which is disposed in the hollow body part 15 and which is mounted for vertical rocking movement by pivot means extending transversely with respect to the longitudinal axis of the machine. The pivot means may be in the form of screws 23 extending through the sides of the frame 10 and having pin projections 24 upon which the member 22 is fulcrumed.

The member 22 may be constructed to include a transversely extending bar portion 25 into which the pin projections 24 extend, and may also include spaced arms 26 which extend forwardly from the bar portion 25 towards an opening 27 in the end wall of the hollow frame part 15. The arms 26 may be connected by another bar portion 28 which extends transversely of the machine just inside of the opening 27. From the arrangement just described it will be seen that the member 22 is pivoted on the frame 10 for swinging or rocking movement in a vertical plane and about the pivot axis provided by the projections 24.

The washer feeding fingers 11 and 12 are mounted on the rocking carrier member 22, and such mounting may be accomplished, for the finger 11, by providing the same with a pair of 5 vertically spaced supporting arms 30 and 31 which extend, respectively, above and below the bar portion 25 of the carrier. The washer feeding finger 12 may have a similar pair of vertically spaced supporting arms 32 and 33 which 10 also extend, respectively, above and below the bar 25. The arms 30 and 31 of the finger 11 and the arms 32 and 33 of the finger 12 are spaced apart vertically substantially the same distance, but the arms 32 and 33 are vertically off-set so 15 as to extend over the arms 30 and 31 in crossing relation thereto adjacent the transverse bar portion 25. A vertical pivot pin 34 carried by the transverse bar portion 25 extends through the pairs of arms of the fingers 11 and 12 at their 20 crossing points and provides a pivot upon which these fingers have lateral swinging movement. The pairs of arms have bearing cooperation with each other and with the transverse bar portion 25 so that the fingers 11 and 12 are supported 25 thereon and have lateral swinging movement about the pivot pin 34 in substantially the same horizontal plane.

As a feature of my invention I provide proportional movement mechanism interconnecting the 30 fingers 11 and 12 so that when either finger is swung laterally of the frame 10 the other finger will be moved substantially proportionately therewith. This proportional movement mechanism may be located forwardly of the pivot pin 35 34, that is on the side thereof opposite to the fingers 11 and 12, and may include a pair of projecting lever arms 35 and 36. The arm 35 may be an extension of the finger supporting arm 30 and the lever 36 may be an extension of the 40 finger supporting arm 33. A longitudinally extending guide member, preferably in the form of a pin or rod 37, may be connected with the bar portion 25 to extend forwardly therefrom through a threaded opening of the transverse bar portion 45 28 and also through the opening 27 of the hollow frame portion 15. A guide block or member 38 may be mounted on the rod 37 for sliding movement therealong. The upper end of the guide block 38 may be connected with the lever arm 35 by a link 39 and the lower end of this guide block 50 may be connected with the lever arm 36 by a similar link 40. From the arrangement just described it will be seen that lateral swinging of either the finger 11 or the finger 12 will cause 55 movement to be transmitted from one finger to the other through the lever arms 35, 36, the links 39, 40 and the guide block 38. Swinging of the fingers 11 and 12 toward each other, that is inwardly toward the longitudinal axis of the machine, will cause the guide block 38 to move forwardly along the rod 37 toward the opening 27 60 of the frame. Separating movement of the fingers 11 and 12, that is movement thereof away from the longitudinal axis, will cause the guide block 38 to be moved along the rod 37 toward the pivot pin 34.

I prefer to have the fingers 11 and 12 in normally separated or divergent relation, as shown in Fig. 1, and to this end I may provide a compression spring 41 which may be disposed around the guide rod 37 to press against the guide block 38. An adjustable abutment for the spring 41 70 may be provided in the form of an adjusting screw 42 which engages the threaded opening of 75 the transverse bar portion 28 and has an open-

ing accommodating the guide rod 37. The screw 42 may extend outwardly through the frame opening 27 as a manually operable adjusting member which is accessible from the outside of the hollow frame part 15.

The bottom plate section 17 of the frame may be provided with a pair of flanges 43 depending therefrom on opposite sides of the longitudinal center line of the machine to form a guide channel 43' which receives certain pins of the mold. 5 The fingers 11 and 12 may be provided, respectively, with depending flange portions 44 and 45 which normally extend in diverging relation similar to the diverging relation of the fingers themselves. These flanges 44 and 45 of the fingers start adjacent the rear end of the channel forming flanges 43, and this starting point is adjacent the axis of the vertical pivot pin 34. As the machine is moved over the mold with certain of the pins engaging in the channel formed by the depending flanges 43, other mold pins will strike the flanges 44 and 45 and will cause lateral swinging of the fingers 11 and 12 sufficient to direct the mold pins into proper cooperation with the washer feeding means of these fingers.

The bottom plate section 18 may also be provided with depending flanges 46 defining a guide channel 46' which is aligned with the guide channel formed by the flanges 43. The pins which engage in the channel 43' also engage in the 30 channel formed by the flanges 46 and are directed thereby to the washer feeding device 13.

As another feature of my invention I provide each of the main washer feeding fingers 11 and 12 with a second or auxiliary washer feeding finger, the auxiliary finger for the main finger 11 being the finger 47 and the auxiliary finger for the main finger 12 being the finger 48. As seen in Fig. 1 of the drawings the auxiliary fingers 47 and 48 lie to the outside of the main fingers 11 and 12, and also lie in substantially the same horizontal plane as the main fingers. The auxiliary fingers are preferably shorter than the main fingers and are supported on the main fingers at an intermediate point thereof. The finger 47 is 45 pivotally connected with the main finger 11 by suitable pivot means 49 which permits this finger to swing laterally outwardly relative to the main finger. Similarly, the finger 48 is connected with the main finger 12 by pivot means 50 which 50 permits the auxiliary finger to swing outwardly from the main finger. Such outward swinging of the auxiliary fingers 47 and 48 is desirable because it permits these fingers to cooperate with mold pins which are spaced outwardly from the 55 main fingers with which the main fingers 11 and 12 cooperate.

Each of the washer feeding fingers 11, 12, 13, 47 and 48 includes an escapement through which washers are permitted to be individually drawn 60 by the mold pins as the fingers move thereover, but which prevents washers from dropping out of the fingers at other times. This escapement may be of similar construction for each of the fingers and, therefore, only one escapement will 65 be described in detail. The escapement may comprise a pair of cooperating members 52 and 53 both of which are movable relative to the finger on which they are supported. The member 52 is a washer guiding member and, as such, has 70 an opening or channel 54 preferably of cylindrical cross-section to which a series or stack of washers in regular order is fed. The washers are supported and normally retained in the guide channel 54 by engagement of the lowermost 75

washer with a pair of inwardly extending shoulders 55 on the member 53. The forward wall of the guide channel 54 is provided with a slot 56 which accommodates the mold pin and the bottom of the member 53 is provided with a similar slot 57 between its shoulders 55. The slot of the member 53 directs the mold pin into the central opening of the lowermost washer so that the washer will be impaled on the pin.

10 The member 53 includes an inclined part 58 in which the slot 57 is formed and which is engaged by, and tilts, the lowermost washer so that the opening of this washer will be presented to the mold pin. This member also includes a 15 forwardly extending stem part 59 which is slideable on the lower part of the finger. The member 52 is supported on the finger and connected therewith by a transverse pivot 60 which permits swinging of this member in a direction to move the 20 bottom end of the guideway 54 toward or from the member 53. The member 52 may be provided with depending lugs 61 at opposite sides thereof which engage in recesses of the member 53. These lugs assist in retaining the member 53 in 25 properly aligned relation to the member 52.

The supply of washers may, as already mentioned, be in the form of a series or stack extending above the escapement member 53. Such a stack of washers may be provided for each finger and may be retained in the desired regular order by a guide wire 62 upon which the washers are strung. The wire may be suspended from the upper end of a bracket 63 which is carried by the 30 escapement member 52.

35 When the escapement device of one of the fingers passes over a mold pin, the pin engages in the opening of the lowermost washer and displaces this washer from the stack. This action is carried out by the pin pulling the washer out between the members 52 and 53. Sufficient space 40 for the withdrawal of the washer is provided by lifting of the member 54 on its pivot 60 in opposition to the spring 64 and accompanied by limited shifting of the member 53. As the washer moves out from beneath the member 52 the top 45 of the mold pin passes through the slot 56, at which time the depending portions 65 forming the sides of this slot hold the washer on the pin.

From the construction and arrangement of the 50 fingers 11, 12, 47 and 48 and the mounting means provided therefor, it will be seen that these fingers being carried by the member 22 have more or less movement in a vertical plane by reason of the member being mounted on the transverse pivot means 24. At the same time the main fingers 11 and 12 have relative lateral swinging movement on their pivot pin 34 and the auxiliary fingers 47 and 48 on their pivots 49 and 50. By reason of these lateral and vertical movements 55 it will be seen that as the machine is moved over the mold, the fingers can readily accommodate themselves to mold pins of varying height and of variable lateral spacing. The movement of the member 22 and of the fingers in the vertical plane may be controlled by providing a compression spring 66 which acts upon a portion 67 of the member 22 and a flat spring 68 which acts on the transverse bar 28. These springs act in a direction to normally depress the fingers so that a desired positive engagement with the mold pins 60 will always be obtainable. If desired, a stop screw 69 may be provided for cooperation with the bar part 28 for determining and adjusting the lowermost position of the fingers relative to the bottom plate of the machine.

75 The auxiliary fingers 47 and 48 which, as above

explained, are carried by the main fingers 11 and 12 and have pivotal connection therewith, may be normally urged toward the main fingers by means of spring 69'. These springs may be tension springs extending between and connected with the upwardly extending brackets 63 of the main and auxiliary fingers. Each of the auxiliary fingers 47 and 48 may also be provided with a wing-like projection 70 on the escapement member 53. This wing projection is adjacent the outer edge of each auxiliary finger and extends outwardly away from the depending flanges 44 and 45. As the machine is moved over the mold, certain of the pins will engage these outwardly extending wings or flanges 70 and cause the auxiliary fingers to be swung relative to the main fingers so that these mold pins will be directed into the slots of the auxiliary fingers to withdraw washers therefrom.

For yieldably supporting the machine on the 20 mold plate I may provide the frame with a pair of laterally spaced rocker arms 71. These rocker arms are pivoted on the frame by means of pivot screws 72 and have lever portions 73 to which tension springs 74 are connected. The engagement 25 of the rocker members 71 with portions of the mold prevents lateral tipping of the machine while it is being moved over the mold pins, and also causes flexing of the springs 74 to yieldably support the leading end of the machine on the 30 mold.

From the foregoing description and the accompanying drawings it will now be readily seen that I have provided an improved washer placing machine having a novel finger arrangement and 35 finger supporting means, by virtue of which the fingers have both vertical and lateral swinging movement. It will also be seen that in my improved washer placing machine certain of the fingers are in the form of auxiliary fingers carried 40 by main fingers and that this arrangement contributes to the simplicity of construction and the satisfactory operation of the machine.

While I have illustrated and described my improved washer placing machine in a somewhat 45 detailed manner, it will be understood, of course, that I do not wish to be limited to the precise details and arrangements illustrated and described, but regard my invention as including such 50 changes and modifications as do not involve a departure from the spirit of the invention and the scope of the appended claims.

Having thus described my invention I claim:

1. A device for placing washers on pins comprising a frame, a movable washer feeding finger, and a second washer feeding finger carried by the 55 first finger and movable relative thereto.

2. A device for placing washers on pins comprising a frame, a washer feeding finger pivoted for movement laterally of said frame, and a second washer feeding finger carried by the first finger and movable laterally relative thereto.

3. A device for placing washers on pins comprising a body having an opening at the bottom thereof, a washer feeding finger pivoted for lateral movement in said opening, an auxiliary washer feeding finger pivoted on the first finger for relative lateral movement in said opening, and means 65 for supplying washers to each finger.

4. A device for placing washers on pins comprising a foot-like body having an opening in the bottom thereof, a washer feeding finger pivoted for lateral swinging movement in said opening, and a second washer feeding finger pivoted on an 70 75

intermediate part of the first finger for relative lateral swinging movement in said opening.

5. A washer placing machine comprising a body having an opening at the bottom thereof, a 5 pair of main washer feeding fingers on opposite sides of the longitudinal center-line of the body and pivoted for lateral swinging movement toward and from each other in said opening, and a second washer feeding finger at the outside of 10 each main finger and pivoted thereon for relative lateral movement.

6. A washer placing machine comprising a frame, a member connected with said frame by a pivot extending transversely with respect to the 15 longitudinal axis of the frame, a washer feeding finger carried by said member and movable in a vertical plane by swinging of said member about said pivot, and means pivotally connecting said finger with said member for swinging of the finger 20 laterally relative to the frame, said frame being a plane-like body having a substantially flat bottom provided with an opening in which said finger has vertical and lateral movement by reason of said pivots.

25. 7. A washer placing machine comprising a frame having an opening at the bottom thereof and a hollow part adjacent said opening, a member in said hollow part and connected with the frame by a pivot extending transversely with respect to the longitudinal frame axis, a washer feeding finger carried by said member and movable in a vertical plane in said opening by swinging of said member about said pivot, and means pivotally connecting said finger in said opening 30 and with said member for swinging of the finger laterally relative to the frame.

40. 8. A washer placing machine comprising a frame, a member connected with said frame by a pivot extending transversely with respect to the longitudinal axis of the frame, a washer feeding finger carried by said member and movable in a vertical plane by swinging of said member about said pivot, means pivotally connecting said finger with said member for swinging of the finger 45 laterally relative to the frame, and a second washer feeding finger carried by the first finger and pivoted therewith for relative lateral swinging movement.

9. In a device for placing washers on pins, a 50 pair of movable main washer feeding fingers, an auxiliary washer feeding finger on each main finger and movable relative thereto, and proportional movement mechanism operatively connecting said main finger.

55. 10. In a washer placing machine, a frame, a member connected with the frame by pivot means extending transversely with respect to the longitudinal axis of the machine, a vertical pivot carried by said member and disposed adjacent said 60 axis, and a pair of washer placing fingers carried by said member and connected therewith for lateral swinging movement on said pivot.

11. In a washer placing machine, a frame, a member connected with the frame by pivot means 65 extending transversely with respect to the longitudinal axis of the machine, a vertical pivot carried by said member and disposed adjacent said axis, a pair of washer placing fingers extending substantially longitudinally of the frame at one 70 side of said pivot and adapted for lateral swinging movement thereon, and motion transmitting

means extending from the fingers at the other side of the pivot.

12. In a washer placing machine, a frame, a member connected with the frame by pivot means extending transversely with respect to the longitudinal axis of the machine, a vertical pivot carried by said member and disposed adjacent said axis, a pair of washer placing fingers extending substantially longitudinally of the frame at one side of said pivot and adapted for lateral swinging movement thereon, each of said fingers having an arm extending in the other direction from said pivot, and proportional movement linkage connecting said arms. 5

13. In a washer placing machine, a frame, a member connected with the frame by pivot means extending transversely with respect to the longitudinal axis of the machine, a vertical pivot carried by said member and disposed adjacent said axis, a pair of washer placing fingers extending substantially longitudinally of the frame at one side of said pivot and adapted for lateral swinging movement thereon, each of said fingers having an arm extending in the other direction from said pivot, guide means having a part movable 20 therealong, and a link connecting each of said arms with said movable part. 25

14. In a washer placing machine, a frame, a member connected with the frame by pivot means extending transversely with respect to the longitudinal axis of the machine, a vertical pivot carried by said member and disposed adjacent said axis, a pair of washer placing fingers extending substantially longitudinally of the frame at one side of said pivot and adapted for lateral swinging movement thereon, each of said fingers having an arm extending in the other direction from said pivot, a guide pin carried by said member and extending substantially in the direction of said arms, a part movable along said guide pin, 30 a link connecting each of said arms with said part, and a spring on the guide pin acting on 35 said part.

15. In a washer placing machine, a plane-like frame having an opening at the bottom thereof 40 and a hollow part adjacent said opening, a member disposed in said hollow part and connected with the frame by pivot means extending transversely with respect to the longitudinal axis of the frame, a pair of main washer feeding fingers 45 carried by said member and movable vertically by swinging of said member about said pivot means, pivot means on said member adjacent said longitudinal axis and about which said fingers have lateral swinging movement, a second finger having pivotal connection with each main finger for lateral swinging relative thereto, proportional movement linkage connecting said main fingers including spring means normally influencing movement of the main fingers, and an adjustment 50 for said spring means projecting from the hollow frame part. 55

16. In a washer placing machine, a frame adapted for movement over a mold plate and having washer feeding fingers thereon, and means 60 for yieldably supporting the machine comprising a rocker pivoted on the frame for engagement with the mold plate and a spring resisting movement of the rocker. 65
